US0D1101587S

(12) **United States Design Patent** (10) **Patent No.:** **US D1,101,587 S**
(45) **Date of Patent:** **** Nov. 11, 2025**

(54) **COMBINED VISUAL INDICATOR AND ABOVE-GROUND STORAGE TANK**

(71) Applicant: **Reign 1, LLC**, Summerland Key, FL (US)

(72) Inventors: **Richard Vanek**, Summerland Key, FL (US); **Rodney Montrose**, Pensacola, FL (US); **Donald Connor**, El Dorado, AR (US)

(**) Term: **15 Years**

(21) Appl. No.: **29/975,184**

(22) Filed: **Nov. 27, 2024**

Related U.S. Application Data

(63) Continuation-in-part of application No. 29/904,695, filed on Oct. 10, 2023, now Pat. No. Des. 1,076,697, (Continued)

(57) **CLAIM**

The ornamental design for a combined visual indicator and above-ground storage tank, as shown and described.

DESCRIPTION

FIG. 1 is a perspective view of a visual indicator for combined visual indicator and above-ground storage tank; FIG. 2 is an exploded view thereof;

FIG. 3 is a front view thereof;

FIG. 4 is a rear view thereof;

FIG. 5 is a side view thereof; and

FIG. 6 is a front view of combined visual indicator and above-ground storage tank; and,

FIG. 7 is a bottom-up view thereof.

The broken line showing of combined visual indicator and above-ground storage tank is for the purpose of illustrating portions and forms no part of the claimed design.

1 Claim, 7 Drawing Sheets
